UNITED STATES PATENT OFFICE

2,100,510

TELEPHONE SYSTEM

Reinhold Hoefer, Berlin-Gatow, and Kurt Wollack, Berlin, Germany, assignors to Siemens & Halske Aktiengesellschaft, Siemensstadt near Berlin, Germany, a corporation of Germany

Application May 7, 1936, Serial No. 78,396
In Germany May 10, 1935

18 Claims. (Cl. 179—18)

The invention relates to a circuit arrangement for automatically operated telephone systems which are exposed to considerable violent shocks or other disturbances.

5 In such systems, for example on warships in which resilient mounting of the devices (frames, selectors and relays) does not suffice to maintain the connecting devices in the position taken up when a call is proceeding, release of the connection can take place on the occurrence of a considerable shock and thus the calling subscriber has to set up the connecting path once more.

Also in such systems the selectors set by impulses cannot be used since shocks occurring during dialling result in false connections. This disadvantage is obviated according to the invention in that after the connection has been released by the mechanical influencing (for example by a shock) of the switching devices (relays), which 15 take up a particular position (working or rest position) while a call is in progress, switching means become automatically operative which cause a re-establishment of the connection between the two previously connected subscribers.

20 The invention also aims at setting the selector switch on the desired connecting line efficiently while dispensing with the necessity for transmitting impulses for the purpose of setting the selector, this being achieved in a simple and practical manner in that a relay group in the exchange is influenced from a calling subscriber's station over characterizing lines, this relay group characterizing the contact set of the desired subscriber's station at a selector serving to set up the connection which is at the disposal of a calling station.

25 An embodiment of the invention is represented in Figs. 1 and 2 of the attached drawings. This represents a system in which on initiating a call, selectors seek out the calling subscriber's line and a further selector is set on the desired subscriber's line by means of the application of potential (caused by the calling subscriber) to the desired connection. Fig. 3 is a modification of the call initiating means on a line.

30 The individual switching operations for establishing a call, for example between subscriber N, Fig. 1, and subscriber N¹ in Fig. 2 are as follows:

When the subscriber N takes up his receiver the following circuit is closed: negative, winding I of relay R, contact 8t, lead 9, over the loop of the subscriber's station N, contact 10t and positive. Relay R energizes and closes contacts 11r and 12r. The calling subscriber is characterized at wiper d of the call finder AS2 by contact 11r. By the closing of contacts 12r the following circuit is set

up: positive, contact 12r, 13t, 14y, relay R2, thermo-relay Th and negative. Contacts 15r2, 16r2 and 17r2 are closed by relay R2. The testing circuit over wiper d is prepared by contact 17r2. The following circuit is established for the rotary magnet DAS1 by contact 15r2; positive, relay interrupter RU, contacts 18p and 15r2, rotary magnet DAS1, and negative. Over contact 16r2, the following circuit is closed: positive, relay interrupter RU, contacts 19p, 16r2, rotary magnet DAS2 and negative. By means of the relay interrupter RU the driving magnets DAS1 and DAS2 are operated simultaneously and thus the call finders AS1 and AS2 are advanced simultaneously. The simultaneous stepping of the two call finders continues until the testing circuit is established over wiper d of call finder AS2. The testing circuit passes over: positive, contacts 20v and 17r2, windings II and I of relay P, contact 21z, wiper d of call finder AS2, contact 11r, winding II of relay R, contact 22r, winding I of relay T and negative. In the above circuit relay T energizes and opens contacts 8t and 10t. The calling circuit over winding I of relay R is thus broken. Relay R locks up over its winding II in the testing circuit. Relay T at contact 13t breaks the circuit for relay R2 and the thermo-relay Th. If for any reason the testing circuit over wiper d of the call finder AS2 is not established in a given time the thermo-relay Th energizes and closes contact 33h. Thus the call impulse given by contact 12r is transmitted to the lead 34 which leads a second call finder group.

35 In the testing circuit relay P is energized and by opening contacts 18p and 19p brings the call finders AS1 and AS2 to rest. Relay P closes contacts 23p to 29p. Switching through of the speaking line takes place over contacts 23p and 24p so that the feeding-bridge-relay is energized over: negative, winding I of relay I, winding I of relay A, contact 23p, wiper a of call finder AS1, lead 7, over the loop at the subscriber's station N, lead 1, wiper b of call finder AS1, contact 24p, winding II of relay A, winding II of relay I and positive.

40 Relay I does not energize in the feeding circuit since it is arranged as a differential relay. Relay A effects the short-circuiting of winding II of relay P over contacts 30a and 31p so that the calling subscriber's line is guarded in the known manner. Relay V is energized over: positive contact 32a, relay V and negative.

45 By the closing of contacts 25p to 29p the characterizing relays II to XI are brought under the influence of the calling station.

In the embodiment described two selectors AS are used for setting on a calling line. One selector may, however, be used just as well, this selector possessing the same number of wipers as the other two selectors together.

If the calling subscriber wishes to converse with the subscriber connected to contact I of the selector D3, positive potential must be applied to the fixed contact I of wiper e of the switch D3. For this purpose it is necessary for the contacts 35I, 36II, 37VI, 38VIII and 39XI to be closed. Accordingly the relays I, II, VI, VIII and XI must be energized. This may be achieved in the embodiment in Fig. 1 by the calling subscriber N operating the keys T1, T2, T3, T4 and T5. The keys T1 to T5 are locking keys which remain operated until the subscriber replaces his receiver. By operating key T1 positive potential is applied to the lead I so that the differential relay I occurring in the feeding circuit is energized. By operating the key T2 a circuit is set up over: positive, T2, lead 2, wiper c of call finder AS1, contact 25p, relays II, III and IV and negative. By means of T3 the circuit over: positive, key T3, lead 3, wiper d of call finder AS1, contact 26p, relays V and VI and negative, is closed. Key T4 causes a circuit for relays VII and VIII to be set up. The circuit passes over positive, key T4, lead 4, wiper a of call finder AS2, contact 21p, relays VII and VIII and negative. Over the circuit: positive, key T5, lead 5, wiper b of call finder AS2, contact 28p, relays IX, X and XI and negative, the relays IX, X, XI are energized. Thus all the characterizing relays I to XI are operated. This merely causes the characterizing of the subscriber connected to contact I of the switch D3 by relays I, II, VI, VIII and XI over contacts 35I, 36II, 37VI, 38VIII and 39XI. The connection of potential to another contact cannot be effected by the additional energization of the other relays III, IV, V, VII, IX, and X.

According to the embodiment it is necessary before taking up the receiver at the calling station to first depress the characterizing keys T1 to T5 so that the characterizing relays are energized directly after the setting of the call finders AS1 and AS2 on the calling subscriber's line. When after the switching through of the line at the contacts 23p and 24p the feeding-bridge relay A also energizes the circuit for the rotary magnet DM3 of the switch D3 is closed over: positive, relay interrupter RU, contacts 59c, 40p2 and 41a, rotary magnet DM3 and negative. The wipers of the switch D3 are advanced until the wiper e reaches the contact indicated by the characterizing relays I—XI. In the present case the switch D3 has only taken one step before reaching the contact to which the desired subscriber is connected. The characterizing circuit over wiper e passes over: negative, relay C, contact 42a, wiper e in position I, contacts 39IX, 38VIII, 37VI, 36II, 35I and positive. Contact 59c is opened by relay C and the switch D3 is just brought to rest. Relay P2 is energized over: positive, windings I and II of relay P2, contact 43c, wiper c of the switch D3, winding II of relay R1, windings II and I of relay T10, and negative. The disconnection of the calling circuit for the desired subscriber N1 is cut off by relay T10 in a manner which is not represented.

By closing contact 44p2, winding I of relay P2 is short-circuited and thus the desired subscriber is guarded in the known manner. By the closing of contacts 45p2 and 46p2 the speaking line is switched through. A circuit is established for the direct current bell over negative, slow interrupter

LU, resistance W, contacts 47p2 and 48y, wiper d of the switch D3, bell Wk and positive. When the called subscriber N1 replies by taking up his receiver, the following feeding circuit is established: negative, winding I of relay Y, contact 45p2, 5 wiper a of switch D3, contact 49XV, over the loop of the subscriber's station N1, contact 50XV, wiper b of the switch D3, contact 46p2, winding II of relay Y and positive. Relay Y at contact 48y breaks the circuit for the direct current bell Wk. 10 Relay Y is kept up independently of the called subscriber over: positive, contacts 51p, 52y, winding III of relay Y and negative.

If the desired subscriber is engaged, relay P2 cannot energize. The busy signal is applied over contacts 53e, 54c and 55p2 to winding III of relay Y. The busy signal is transmitted inductively to windings I and II in the speaking path so that the calling subscriber can perceive the busy signal. Moreover, the following circuit is closed: positive, 15 interrupter LU, resistance W, contact 56p2, winding II of the choke-coil Dr, contacts 57c and 58e and positive. An intermittent signal is produced which is transmitted inductively to the winding I of the choke-coil Dr, so that the desired subscriber 20 who is engaged is also informed of the presence 25 of a call.

If the feeding bridge relay A is energized after the setting of the selectors AS1/AS2 and relay C does not energize over wiper e of the selector 30 D3 within a given time, relay Th1 is energized. The circuit passes over: positive, contacts 60a, 61c, 62z, thermo-relay Th1 and negative. The thermo-relay Th1 opens contact 63th1 and closes contact 64th1. Relay Z energizes over positive, 35 contact 64th1, relay Z, resistance W2 and negative. Relay Z locks up independently of contact 64th1 over contact 65z. At contact 21z, relay Z opens the testing circuit over wiper d of the selector AS2. Relay P and with it relays 40 A, V and the characterizing relays I—XI release. Since the testing circuit over wiper d of the call finder AS2 is broken, the subscriber's relay T releases. Relay R locks up in the calling circuit. By means of the thermo-relay Th1 45 the circuit for relay Z and thus the break at contact 21z is maintained until relay Th has caused switching over on to another call finder group at contact 33th, over: positive, contacts 12r, 13t, 14y, relay R2, relay Th and negative. When this 50 switching over takes place, contact 64th1 is open and contact 63th1 closed, so that relay Z releases. Thus, the devices of the first set of equipment which has been taken into use are released. Since the calling condition and the characterizing condition of the calling station are still in 55 existence, a connection is established in the same way over a further equipment set in the same way as was described for the equipment shown in the drawings.

If the subscriber reached over selector D3 is engaged and the calling subscriber is a specially privileged subscriber who is provided with the key T6, then this privileged station can switch on to the existing connection.

By operating the key T6, the circuit over positive, key T6, lead 6, wiper c of the switch AS2, contacts 29p, relays L and E and negative is closed. Relay E opens contact 66e and closes contacts 67e and 68e. The calling subscriber is 70 thus connected with the desired subscriber independently of the energizing of the testing relay P2 over contacts 67e/68p2 and 68e/70p2. By the opening of contacts 53e and 58e, the engaged signal for the calling subscriber and the tick- 75

ing signal for the called subscriber are disconnected. The privileged subscriber can also set different ringing independently of the interrupter LU. In the circuit which is closed by the key 5 **T6**, relay L occurs. Relay L closes a ringing circuit independent of contact **48y** and **47p2** over negative, resistance **W1**, contact **71z**, wiper **d** of selector **D3**, bell **Wk** and positive.

A subscriber is also in the position to connect together all the subscribers of a system in a conference call. For this purpose the calling subscriber according to the embodiment, merely depresses the key **T2** and takes up his receiver. After switches **AS1** and **AS2** have been set in 10 the manner already described, the relays **II**, **III** and **IV** energize by the operation of the key **T2**. On account of the operation of these relays, contact **31** of the selector **D3**, is characterized by the opening of contact **72II** and the closing of 15 contact **73II**. The characterizing circuit over wiper **c** of the switch **D3** passes over negative, relay **C**, contact **42a**, wiper **e** of selector **D3** in position **31**, contacts **73II**, **14V**, **76VII**, **77IX**, **78I** and positive. The selector **D3** is advanced to 20 contact **31** and is then brought to rest in the manner previously described. Over wiper **c** and contact **31** the following circuit is closed; positive, windings **I** and **II** of relay **P2**, contact **43c**, wiper **c** of the selector **D3** in position **31**, relay **25 XV** and negative. In the circuit just mentioned relay **P2** energizes and effects the switching operations already described. Relay **XV** opens contacts **49XV** and **50XV** and closes contacts **79XV** and **80XV**. The subscriber's line of the station 30 **N1** is switched over on to the common line connected to contact **31**. Contact **81XV** closes the ringing circuit. Relay **XV** in the same way as for the subscriber **N1** represented, causes the switching over of the lines of all the subscribers 35 and the ringing circuit on to the line connected to contact **31** of the selector **D3**, so that all the subscribers are called and are connected to the common line connected to contact **31**. The called subscribers reply so that the calling party knows 40 which of the subscribers are taking part in the conference call.

The release of a call is brought about in the following manner: When the subscriber **N** replaces his receiver, the feeding bridge relay **A** releases. Relay **A** opens the testing circuit over relay **P** and wiper **d** of selector **AS2**. Relay **P** releases. At contact **32a** relay **A** breaks the circuit for relay **V** so that this relay also returns its contact to normal. At contact **42a**, the circuit for relay **C** is broken and this releases and by opening contact **43c**, breaks the circuit for relay **P2**. Relay **P2** opens contacts **45p2** and **46p2** so that the line is disconnected and the feeding bridge relay **Y** is caused to deenergize. By 45 the opening of contact **43c**, the relays reached in the testing circuit over wiper **c** of selector **D3** (for example **R1**, **T10** or **XV**) are released. By the interruption of the testing circuit of switch **AS2** over wiper **d** at contact **30a**, the subscribers' 50 relays **R** and **T** are returned to normal. On the replacement of the receiver at the calling station, the characterizing keys **T1**—**T2** also return to normal. Thus all the switching devices taken into use are restored to normal.

If the system is exposed to vibration from any cause, the relays influencing the condition of the call (subscriber's relay **R**, feeding bridge relay **A**, testing relay **P** and relay **Z**) cannot move the contacts into a position other than 55 that necessary for the call set up. If, however,

on account of shock, the position occupied by a relay is altered and thus release of the call is brought about, then according to the present arrangement, the connecting path established over the selectors is immediately re-established 5 after the shock.

If, for example, the armature of relay **A** is returned to its normal position by means of a shock, the operated contacts of relay **A** are also opened, and the circuit for relay **P** is broken at 10 contact **30a**. Relay **P** returns its contacts to normal. Since the characterizing of the desired subscriber still exists over the characterizing keys **T1**—**T5** and the calling circuit for the calling station is again re-established after the interruption of the testing circuit, the call is re-established 15 in the same manner as has already been described. Since the subscriber to whom a call has been set up has not yet replaced his receiver, relay **Y** is immediately energized after the setting of selector **D3** on the line of this subscriber, without a second call to the subscriber in question having to be initiated.

If on account of a shock, only the armature of relay **P** is returned to the rest position, relay **A** is deenergized by the opening of contacts **23p** and **24p**. Release takes place in the manner already described. On account of the receiver being still removed from its position, and since the characterizing condition for the desired subscriber still exists, the connecting path is immediately re-established. While a call is in progress, the contacts of relay **Z** are in the rest position. If, on account of shock, the armature of relay **Z** is brought into the working position, 35 the circuit for relay **P** is broken at contact **2iz** and the circuit for relay **A** is broken at contacts **23p** and **24p**. Release of the call again takes place, the call being subsequently re-established without the calling subscriber having to 40 execute any special switching operation.

According to the embodiment in Fig. 1 a subscriber is provided with a series of five keys, **T1**—**T5** for characterizing the desired subscriber, these keys operating on eleven characterizing relays for characterizing **31** subscribers' stations. In order to simplify the mode of operation at the calling subscriber's station, a rotary switch can be arranged in place of the keys **T1**—**T5** as, for example, is shown in Fig. 3. This rotary switch possesses as many contact positions as there are subscribers' stations to be reached, and on setting the rotary switch on a particular contact, positive potential is applied to the various characterizing leads according to the wiring of the leads **1**—**5**. If a calling subscriber wishes to set up a call to a station connected to contact **1**, he sets the rotary switch on contact **1**. Over the lead connected to contact **1** of the rotary switch, positive potential is applied to the leads **1**, **2**, **3**, **4**, and **5**, so that the characterizing relays which are reached over these leads are operated. Thus the subscriber, instead of having to operate five keys, has only to set the rotary switch on contact **1**.

Which of the keys according to the embodiment shown in Fig. 1 are to be depressed for characterizing the various subscribers may be seen from the pyramidal arrangement of the connecting contacts connected to wiper **e** of the selector **D3**. For example in order to characterize the subscriber connected to contact **5** it is necessary for the contacts **35I**, **36II**, **82VIII**, **83XI** to be closed. Thus the relays **I**, **II**, **VIII** and **XI** 75

must be energized. This is effected by depressing the keys T1, T2, T4 and T5. If the subscriber connected to contact 13 is wanted then in order to characterize this subscriber the contacts 35I, 84VII and 85IX must be closed. Relays I, VII and IX have to be energized. This is effected by depressing keys T1, T4 and T5. If the subscriber who is connected to contact 23 is wanted the contacts 86IX and 87III have to be closed, for this purpose relays IX and III must be energized. This is effected by depressing keys T2 and T5.

What is claimed is:

1. In an automatic telephone system, subscriber controlled switching means for setting up connections between subscribers in the system, and means for automatically resetting an established connection in case it is interrupted.
2. In an automatic telephone system, automatic switching means, means controlled by any subscriber in the system for operating said switching means to establish a connection with any other subscriber, means controlled by said connected subscribers for releasing said switching means and disconnecting said established connection, and means for automatically reestablishing said connection in case said switching means are released other than by the connected subscribers.
3. In an automatic telephone system, automatic switching means, subscriber controlled means for operating said switching means to establish a connection with another subscriber, said switching means remaining operated for the duration of the connection, and means in case said switching means is inadvertently released and the established connection is disconnected for automatically reestablishing said connection independent of any control by the subscriber.
4. In an automatic telephone system, automatic switching means, means controlled by a calling subscriber for initiating the operation of said automatic switching means to establish a telephone connection with a called subscriber, means controlled by said connected subscribers for releasing said switching means responsive to the termination of the call, and means for automatically reoperating said switching means to re-establish the connection between the said subscribers in case the release of said switching means occurs inadvertently and without control by the subscribers.
5. In a telephone system, a plurality of subscribers' lines, a group of relays, automatic switching means, means controlled by a calling line for operating a particular combination of said group of relays in accordance with the line of a called subscriber, said automatic switching means operated in accordance with said combination of relays to establish a connection between the calling and called lines, said automatic switching means and said relays subject to violent shock and thereby released whereby said established connection is released, and means for automatically reoperating said switching means and said relays to reestablish the connection.
6. In a telephone system as claimed in claim 5 in which certain relays in the automatic switching means are released when subjected to violent shock and the established connection released, and in which the said relays are reoperated to again establish the connection with the called line due to the particular calling combination of relays being again operated automatically without control by the calling subscriber.

7. In a telephone system, subscribers' lines, a group of relays, a set of keys at each subscriber's line, said keys operated by a subscriber in certain combinations in accordance with a called subscriber's line to effect the operation of certain ones of said group of relays, automatic switching means controlled by the operated ones of said group of relays to establish a connection with the desired called subscriber's line, said automatic switching means and relays subject to violent shock whereby they are released and said connection disconnected, said operated keys again operating said combination of relays to their operated condition, and means for reoperating said automatic switching means in accordance with the operated combination of relays to re-establish the connection with the called line.

8. In an automatic telephone system wherein the switching apparatus is subject to the influence of violent shock, means controlled by a calling subscriber for characterizing the line of a called subscriber and for maintaining said characterization intact for the duration of the call and at the time of any violent shock, said switching apparatus automatically operated by said characterization to establish a connection with the called subscriber's line, said switching apparatus released and said connection thereby disconnected responsive to the occurrence of a violent shock, and means whereby said switching apparatus automatically reoperates and again establishes the connection under influence of the operated characterizing means.

9. In an automatic telephone system, subscribers' lines, a relay group, characterizing leads extending from said subscribers' lines to said relay group, means controlled by a calling subscriber for operating certain combinations of said relays over certain combinations of said characterizing leads, said combinations of operated relays corresponding to a particular called subscriber's line, and automatic switching means operated in accordance with the operated combination of said relays to establish the connection with the called and calling subscribers' lines.

10. In an automatic telephone system, subscribers' lines, a finder switch for finding a calling line, a second finder switch for finding the called line, and means controlled by the subscriber of a calling line for marking the calling line in the bank of the first finder, for marking the called line in the bank of the second finder, and for initiating the operation of both of said finders to find the marked lines.

11. In an automatic telephone system, subscribers' stations, a relay group, a plurality of characterizing leads extending from said stations, means controlled at a calling subscriber's station for energizing combinations of said characterizing leads in accordance with a called subscriber's station, means for associating said characterizing leads with said relay group to operate combinations of said relays in accordance with the energized characterizing leads, an automatic switch, said combinations of relays marking the called station in the bank of said switch, and means for operating said switch to connect the calling and called stations.

12. In an automatic telephone system as claimed in claim 11 in which the relay group is common to all the subscribers' stations and the number of characterizing leads extending from each station is less than the number of stations that are selectable.

13. In an automatic telephone system, sub-

scribers' stations, characterizing leads extending from each station, a relay group, a finder switch for connecting a calling station's characterizing leads with said relay group, means at the calling station for energizing combinations of said characterizing leads in accordance with a called station's number to operate corresponding combinations of said group of relays, a second finder switch having access to called station lines, said 10 operated combinations of relays marking the called station's line in the bank of the second finder switch, and means responsive to the operation of both of said finder switches for establishing a connection between the calling and 15 called stations.

14. In an automatic telephone system according to claim 13 in which one of the characterizing leads includes the speaking lead of the calling station and the same potential is applied to 20 the particular combinations of the characterizing leads.

15. In an automatic telephone system according to claim 13 in which one of the characterizing leads includes a speaking lead of the calling 25 station, one of said group of relays being included in the speaking lead and furnishing speaking current to the calling station.

16. In an automatic telephone system as claimed in claim 13 in which responsive to the energization of a particular characterizing lead at a calling station and the consequent operation of a particular combination of said group of relays the second finder switch is caused to operate to a position wherein a plurality of called stations are connected simultaneously to the calling station for a conference call. 5

17. In an automatic telephone system according to claim 13 wherein specially privileged stations are enabled to operate special relays of the group over a special characterizing lead, and means controlled by said special relay for connecting the calling station line with a busy called 10 line. 15

18. In an automatic telephone system as claimed in claim 13 in which the means at the calling station for energizing the characterizing leads comprises a locking key connected to each 20 characterizing lead, said keys being released from their operated position by replacement of the receiver on the switchhook of the calling station.

REINHOLD HOEFERT. 25
KURT WOLLACK.
